UNITED STATES PATENT OFFICE.

WILLIAM A. DIELHENN, OF MASSILLON, OHIO.

ADJUSTABLE GARMENT.

No. 920,115.

Specification of Letters Patent.

Patented May 4, 1909,

Application filed September 25, 1908. Serial No. 454,676.

To all whom it may concern:

Be it known that I, WILLIAM A. DIELHENN, a citizen of the United States, resident of Massillon, county of Stark, and State of Ohio, have invented a new and useful Improvement in Adjustable Garments, of which the following is a specification, the principle of the invention being herein explained and the best mode in which I have contemplated 10 applying that principle, so as to distinguish it from other inventions.

My invention relates to garments, and particularly to garments such as petticoats or the like, in which the upper edge or waistband portion is adjustable to various sized waists.

The object of my invention is to obtain an adjustable garment of the above described character which is economical in its construction, simple in its adjustability and efficient in its application.

Said invention consists of means herein-after fully described and particularly set forth in the claims.

25 The annexed drawing and the following description set forth in detail certain means embodying the invention, the disclosed means, however, constituting but one of various mechanical forms in which the principle of the invention may be used.

In said annexed drawing:—Figure 1 is a perspective view of the upper part of a petticoat embodying my invention. Fig. 2 is a view similar to that of Fig. 1, showing the 35 waistband portion of the petticoat adjusted to assume a smaller diameter than is shown in Fig. 1. Fig. 3 is a fragmentary rear elevation of the petticoat showing the placket formed therein and the relation of other 40 parts thereto. Fig. 4 is a fragmentary side elevation of the petticoat. Figs. 5 and 6 are cross sections, on an enlarged scale, taken upon the planes indicated by lines V—V and VI—VI respectively, in Fig. 1. Fig. 7 45 is a cross section on a similarly enlarged scale taken upon the plane indicated by line VII—VII in Fig. 3.

The main or body portion A of the petticoat consists of a plurality of gores a which are stitched to each other in the usual 50 manner, and form the outside upper edge portion of the garment. The rear of the garment is formed with a placket a' of the usual construction and provided with fastening devices, such as the male and female

members a^2 and a^3 of ordinary glove fasteners, as will be readily understood. The inside upper edge portion of the garment is composed of one continuous strip a^4 of fabric, which therefore terminates at the placket 60 and forms a waistband. This strip is stitched to the upper edge portions of the gores in two substantially parallel lines, one being located immediately adjacent to the upper edge of the garment and the other 65 immediately adjacent to the lower edge of the waistband, as shown in Fig. 5, thereby leaving an unobstructed space between the gores and the waistband. That portion a^5 of the front edges of the rearmost gores immediately adjacent to the waistband is not 70 stitched to the latter, whereby an opening into the said unobstructed space is formed. The upper edge portions therefore of each of these rearmost gores forms, in conjunction 75 with that of the waistband immediately adjacent thereto, a pocket in each of which is located an adjusting band B. The rearmost end of each band is secured in the immediate vicinity of the placket, the one band end 80 being secured by the member a^3 of the glove fastening device and the other band end being secured by the member a^2 of such device, these two members passing completely through the gores and waistband, as shown 85 in Fig. 7. The forward ends of these adjusting members B project from their respective openings in the pockets, as shown in the drawing, and are provided with a member of a fastening device such as the 90 hook or an eye of a hook and eye or such as the female member of a glove fastener, the latter being shown in the drawing.

A plurality of the complementary members of the fastening device, such as the male 95 members of a glove fastener, are secured at various points along the upper edge portion of the part of the body portion of the garment adjacent to and forward of the rearmost gores a , as shown. It will therefore be 100 seen that by causing the forward ends of the adjusting bands to engage the various complementary members of the fastening devices, various diameters may be given to the upper or waistband portion of the garment, thereby permitting same to be adjusted to various sized waists. All of the gathered portion or fullness of the garment is thereby 105 confined to the rear portion thereof, at which portion it is least objectionable, it being per- 110

ticularly desirable in petticoats to have the side thereof, or that portion immediately over the hips, given a smooth appearance.

As shown in Fig. 4, that portion of the 5 gores immediately forward of the rearmost gores and adjacent to the waistband are turned under or cut away at an angle so as to remove a portion of the fabric immediately adjacent to the opening of the pocket. Such 10 construction removes any impediment which the upper edge of the gores might form in the path of the fastening members B, as they are slid back and forth. This furthermore reduces the liability of a frayed edge of the garment 15 being produced at this point, the finished appearance of the garment being thereby maintained to the greatest possible extent.

What I claim therefore and desire to 20 secure by Letters Patent is:—

1. In a garment, the combination of a main or body portion provided with a placket; a waistband terminating at said placket, a part of said band and body portion 25 forming a pocket; an adjusting member in said pocket having one end secured and the other free; and means for securing said free end at various points longitudinally of said band.

30 2. In a garment, the combination with a main or body portion; of a waistband consisting of one continuous strip of fabric; a part of said band and body portion forming a pocket having one end open.

35 3. In a garment, the combination with a main or body portion comprising in its structure a plurality of gores; of a waistband; a part of said waistband and body portion forming a pocket terminating with one of said 40 gores.

4. In a garment, the combination with a main or body portion comprising in its structure a plurality of gores; of a waistband consisting of one continuous band of fabric; a 45 part of said waistband and body portion forming a pocket terminating with one of said gores.

5. In a garment, the combination with a waistband; of a plurality of gores stitched to 50 said band along two lines running longitudinally thereof and leaving an intermediate free space forming a pocket; the lateral edge of one of said gores being free from the waistband adjacent to said pocket whereby an 55 opening into the latter is effected.

6. In a garment, the combination with a waistband; of a plurality of gores stitched to 60 said band along two lines running longitudinally thereof and leaving an intermediate free space forming a pocket; the lateral edge of one of said gores being free from the waist-

band adjacently to said pocket whereby an opening into the latter may be effected; the gore contiguous to such above-named gore being removed adjacent to said opening.

65

7. In a garment, the combination of a main or body portion provided with a placket; a waistband terminating at said placket; a part of said band forming a pocket in conjunction with said body portion; an adjusting member in said pocket; means for fastening said placket in its closed position and securing one end of said member, the other end of the latter being free; and means for securing the free end of said member in various positions longitudinally of said band.

70

8. In a garment, the combination of a main or body portion formed at the rear with a placket; a waistband terminating at said placket; means for securing the latter in a closed position; and two adjusting members each having one end secured in the vicinity of said placket and extending forwardly therefrom; and means for securing the forward ends of said members at various points 85 longitudinally of said band.

75

9. A garment provided with a placket, a pocket extending from the latter along the upper edge portion of the garment and having one end open; an adjusting member 90 within said pocket having one end secured to the garment in the vicinity of said placket and the other end projecting from the open end of the pocket; and means for securing such projecting end in various positions longitudinally of said edge portion of the garment.

95

10. A garment comprising the combination of a plurality of gores forming the main or body portion of the garment, such body portion formed at the rear with a placket; means for securing said placket in a closed position; a waistband composed of a continuous strip of fabric; said body portion and waistband jointly forming two pockets 105 extending from the placket forward along the upper edge portion of the garment and respectively terminating with a gore and at or near the side of the garment; an adjusting band loosely placed in each of said pockets 110 and having their rear ends secured in the vicinity of said placket, the other ends of such adjusting bands projecting from said pockets; and means for securing such projecting band ends in various positions along the outside of such upper edge portion of said garment.
